By *John Newborn* Attorney

UNITED STATES PATENT OFFICE.

JOHN C. NEWBORN, OF HAGERMAN, NEW MEXICO.

MATTRESS.

1,382,531.

Specification of Letters Patent. Patented June 21, 1921.

Application filed January 10, 1919. Serial No. 270,491.

To all whom it may concern:

Be it known that I, JOHN C. NEWBORN, a citizen of the United States, residing at Hagerman, in the county of Chaves and 5 State of New Mexico, have invented certain new and useful Improvements in Mattresses; and I do hereby declare the following to be a full, clear, and exact description of the invention, such as will enable others 10 skilled in the art to which it appertains to make and use the same.

My invention relates to improvements in mattresses and has special reference to that class of mattresses employing air as a filler.

15 An important object of my invention is to provide a pneumatic mattress which when not in use, may be folded up into a compact bundle, thus making its use desirable by soldiers and others who require the use 20 of such a mattress which may be folded into a compact bundle.

A further object of the invention is to provide a pneumatic mattress having a pillow formed integral therewith and near one 25 end portion thereof.

A further object of the invention is to provide a pneumatic mattress of the character described which is neat in appearance, easy to inflate and comfortable to sleep on. 30 Other objects and advantages of the invention will be apparent during the course of the following description.

In the accompanying drawings forming a part of this specification and in which like 35 numerals are employed to designate like parts throughout the same,

Figure 1 is a perspective of my improved pneumatic mattress,

Fig. 2 is a central vertical longitudinal 40 sectional view through my improved mattress,

Fig. 3 is an enlarged sectional view through the valve mechanism for inflating my improved pneumatic mattress, and,

45 Fig. 4 is a section taken on line 4-4 of Fig. 3.

In the drawings, wherein for the purpose of illustration is shown the preferred embodiment of my invention, the numeral 50 5 designates the body portion of my improved pneumatic mattress having side members 6 tapering toward the lower ends

thereof. The covering 7 of my improved pneumatic mattress is of a relatively stout cloth, preferably duck. The lower end 8 55 of the mattress may be rounded, as shown, or if desired may be flat.

The upper end of the mattress is provided with a transverse outwardly bulging portion 9 forming a pillow. Arranged within 60 the casing 7 is a rubber casing 10 adapted for the reception of air.

Secured to the end portion 11 of the mattress and extending through the rubber casing 10 is an air inlet valve 12, preferably of 65 the check valve type. A centrally arranged aperture 13 adapted for the passage of air therethrough is normally closed by a disk 14.

A second disk 15 having apertures 16 extending therethrough is permanently secured to the inner wall of the valve 12 which permits of the passage of air into the casing 10.

While I have shown a specific form of air inlet valve, it is obvious that any form of 75 air inlet valve may be used.

In the use of my device, the mattress is laid out flat as shown in Fig. 1 and inflated to the desired pressure by any suitable means and it is ready for use. It will be 80 apparent that the absence of rigid braces, etc., makes it possible to fold the mattress up into a very small space when not inflated.

Having thus described my invention, what 85 I claim is:

A mattress comprising an elongated body constructed from air retaining material and having one of its end walls of a less height than the other end wall so that the top wall will be disposed on an incline when said 90 body rests on a flat support, a fabric cover for said body, means whereby said body may be inflated and deflated, an elongated strip extending transversely of the body adjacent one end and having its end and side edges 95 secured to said body to form a pillow, said body having an opening to permit air to enter said pillow from said body.

In testimony whereof I affix my signature in presence of two witnesses.

JOHN C. NEWBORN.

Witnesses:

M. A. LOSEY,
EVA HELLAN LOSEY.
